UNITED STATES PATENT OFFICE.

IRA D. FULLER, OF VONA, COLORADO.

COIN-COUNTING MACHINE.

1,193,373.

Specification of Letters Patent. Patented Aug. 1, 1916.

Application filed August 11, 1914. Serial No. 856,275.

To all whom it may concern:

Be it known that I, IRA D. FULLER, a citizen of the United States, residing at Vona, in the county of Kit Carson and State of Colorado, have invented certain new and useful Improvements in Coin-Counting Machines, of which the following is a specification.

This invention relates to a coin counting machine, and has for its object to provide a device of this character including a plurality of holders for holding coins of various denominations, and means for ejecting the coins from the several holders and simultaneously recording the money values thereof.

With this and other objects in view, the invention consists in the novel construction, arrangement and formation of parts as will be hereinafter specifically described, claimed and illustrated in the accompanying drawings, in which:

Figure 1 represents a top plan view of the counting machine. Fig. 2 represents a side elevation thereof. Fig. 3 represents a front elevation of the machine. Fig. 4 represents a longitudinal sectional view, on the line 4—4 of Fig. 1. Fig. 5 represents a rear elevation of the dial and several of the cooperating parts. Fig. 6 represents an enlarged detail view, partly in section of the driving means for the dial and recorder. Fig. 7 represents a perspective view of the parts of the recorder actuating means removed from the machine. Fig. 8 represents a perspective view of one of the coin ejectors removed from the machine. Fig. 9 represents a perspective view of the universal bar removed. Fig. 10 represents an enlarged detail sectional view on the line 10—10 of Fig. 1.

Referring to the drawing in detail, wherein similar reference numerals designate corresponding parts throughout the several views, the numeral 5 indicates a pair of spaced side walls having a rear wall and top plate 6 providing a housing and base for the reception of the coin ejecting and recording mechanisms. The front end of the housing is open and a strip 7 is secured transversely of and adjacent the forward end of the plate 6 and is provided with a plurality of apertures 8 of various sizes adapted to receive coins of various denominations introduced in the cylindrical chutes 9 seated in the apertures 8. Slots 10 are formed in

the top plate 6 or in an intermediate plate placed between the top plate and the strip 7 and coin ejectors are slideable longitudinally in the slots or recesses 10. The ejectors 11 are formed with longitudinal openings 12 receiving screws 13 for guiding and limiting the movement of the ejectors. Rearwardly and downwardly directed arms 14 are secured to the forward ends of the ejectors 11 and the rear extremities thereof are directed downwardly, as indicated at 15, a finger 16 being secured to each arm 14 and connected with a spring 17 to normally retain the ejectors in forwardly extended position. A shaft 18 is rotatably mounted in the side walls 5 below the plate 6 and is provided with a plurality of arms adapted to successively engage a depending end 15 of the arm 14 to actuate the ejectors 11 and eject coins from the apertures 8 through the openings 20 communicating with said apertures. The coins ejected from the several apertures drop through suitable openings 21 formed in the plate 6. Interiorly of the side walls 5 a gear wheel 22 is secured on the end 80 of the shaft 18 and meshes with a gear wheel 23 rotatably mounted in said side wall and carrying an operating crank 24.

A plurality of angular brackets 26 are secured to the top plate 6 rearwardly of the series of openings 21 and slidably receive a plurality of horizontally disposed slide bars 27 pivotally secured at their forward ends to pivoted coin-engaging members 28 provided with adjustable screws 29 adapted to 90 be locked in adjusted position by lock nuts 30. The slide bars 27 are normally retained in forwardly extended position by springs 31 secured at their forward ends to the brackets 26 and at their rear ends to upwardly projecting pins 32 secured adjacent the rear ends of the slide bars 27. The adjustable screws 29 project a distance downwardly from the lower face of the pivoted members 28 and are adapted to slide upon 100 the inclined face 33 of a forwardly projecting part of each of the brackets 26 to automatically lift the pivoted member 28 out of engagement with the coin ejected through the opening 20 subsequently to an operation 105 of the registering mechanism, as will be hereinafter clearly described.

A shaft 34 disposed longitudinally of the machine is rotatably supported in bearing members 35 secured to the plate 6. A wheel 110

36 is keyed on the front end of the shaft 34 and is formed with a peripheral channel 37 the walls of which are formed with a plurality of openings slidably receiving pins 38 retained against accidental movement by bands of elastic material disposed in the channel 37 and engaging the medial portions of the pins. One edge of the wheel 36 is formed with ratchet teeth adapted to 10 operate with a spring pawl 39 to prevent the rotation of the wheel in one direction. There are one hundred of the pins 38 in the wheel corresponding to the number of cents in one dollar. The shaft 34 is rotated 15 during the operation of the counting machine by a belt or the like 40 extending over a pulley 41 on the shaft 34, idler pulleys 42 on the intermediate shaft 43 and the large pulley 44 keyed on the front shaft 18.

20 A registering mechanism 47 is secured adjacent the rear end of the plate 6 and is provided with an outwardly directed arm 48 normally retained in lowered position by a spring 49 and carrying at its free extremity 25 a pivoted member 50 engaging the face of a scroll shaped cam 51 keyed on the shaft 34 and having a radial face 52. At each rotation of the shaft 34 the arm 48 is lifted by the cam 51 and drawn downwardly by the 30 spring 49 when the pivoted member passes the radial face 52 of said cam, thus actuating the registering mechanism 47 to register one unit or dollar representing the amount ejected from the counting machine by the 35 operation of the crank handle 24. A rock shaft 53 is pivotally supported below the plate 6 and carries adjacent its opposite extremities upstanding arms 54 and 55. The arm 55 is provided with an angularly directed end 56 disposed horizontally and normally retained in close relation with the rear face of the wheel 36 by the tension of a spring 57 connected at one end with the plate 6 and at the opposite end with the 40 outer arm 54 carried by the shaft 53. The arm 54 is provided with an angularly directed end disposed in a horizontal plane and provided with an adjustable screw 58 that engages against the end of a slide bar 27^a 45 extended a distance rearwardly of the slide bars 27 and constituting a part of the coin operated mechanism operable by coins of the denomination of one dollar.

50 The large opening 8 at the left end of the strip 7 is adapted to receive one dollar pieces, the next opening being adapted to receive fifty cent pieces, the next twenty-five cent pieces, the next ten cent pieces, the next five cent pieces and the end or last opening being adapted to receive pennies. For convenience, the value of the coin adapted to be placed in the various openings in the strip is marked on the latter adjacent each opening. Each of the slide bars 27 is 55 provided with an angularly directed rear end

59 in which are longitudinally adjustable pins 60. The pins 60 carried by the slide bars 27 are adapted to engage and push the pins 38 of the wheel 36 rearwardly to project a distance rearwardly of the rear face 70 of the wheel, whereby the rearwardly projecting end of the pin 38 will strike the angularly directed end 56 of the arm 55 during the rotation of the wheel. The pins 60 carried by the slide bars 27 associated with 75 the penny opening 8 in the strip 7 is arranged so as to push the pin 38 in the wheel 36 adjacent the pin opposite the angularly directed end or abutment 56, while the slide bar 27 associated with the five cent piece 80 receiving opening 8 is provided with a pin so arranged as to engage a pin 38 in the wheel fifth in advance of the abutment 56. The pin 60 associated with the slide bar actuated by ten cent pieces engages the 85 tenth pin 38 in advance of the abutment 56, the pin 60 operated by the ejection of a twenty-five cent piece being adapted to engage the twenty-fifth pin 38 in advance of the abutment, while the pin 60 operable by 90 fifty cent pieces is adapted to engage a pin 38 of the wheel diametrically opposite the abutment 56 or fifty pins in advance of said abutment.

A universal bar 62 is pivotally mounted at 95 63 on the plate 6, extends transversely of the latter and is normally retained in forwardly inclined position by a spring 64. The bar 62 is normally engaged against the pins 32 carried by the bars 27 and is adapted to be 100 actuated by the latter when said bars 27 are moved rearwardly by a coin. One end of the bar 62 is connected with the corresponding end of a lever 65 by a link 66, and the lever 65 is pivotally secured at 67 to one of 105 the end supports 35. The free extremity of the lever 65 terminates adjacent the rear face of the wheel 36 and is normally retained in spaced relation thereto.

As clearly shown in Fig. 5 the free extremity of the lever 65 terminates directly beneath the abutment 56, thereby when the lever is rocked by an operation of the universal bar 62 its free end will move inwardly toward the wheel 36 and push the pin 38, 115 which is in engagement with the abutment 56, forwardly to normal position.

The coins to be counted are placed in the chutes 9 and the hand lever 24 is rotated manually or otherwise to operate the several 120 ejectors 11 and the wheel 36, which latter, as will be understood, is driven by the belt or the like 40. Owing to the arrangement of the arms 19 on the shaft 18 the several ejectors are operated intermittently and successively and during their rearward movement against the tension of the springs 17, the lowermost coins seated within the openings 8 are pushed rearwardly through the openings 20 and against the forward ends of the 130

pivoted members 28. The members 28 and the slide bars 27 are moved a distance rearwardly when the adjustable screws 29 engage the inclined faces of the brackets 26 and cause the pivoted members to move upwardly out of engagement with the coin, permitting the latter to fall downwardly through the opening 20 and into the bottom of the housing. It will be understood that the members 28 are only operable by a coin as the ejectors 11 are not sufficiently long to engage the forward ends of said pivoted members 28. The first coin ejected by either of the four right hand ejectors 11 carries the pivoted member 28 and the slide bar 27 associated therewith rearwardly pushing one of the pins 38 in the wheel 36 rearwardly of the latter by the engagement of the pin 60 therewith. The wheel 36 rotates until the unseated or rearwardly projecting pin 38 strikes against the abutment 56, thus locking the wheel against further rotation until the partially ejected pin 38 is moved to normal position by the free end of the lever 65 operated by the second ejected coin engaged with one of the pivoted members 28 and operating the universal bar 62 through the sliding bar 27, and the pin 32 and rocking the lever 55 through the link 66, as will be understood. The ejection of a one dollar piece from the largest opening 8 in the strip 7 causes the sliding bar 27^a to be moved rearwardly, rocking the rock shaft 53 through the arm 54 and causing the outer arm 55 and the abutment 56 thereof to be moved rearwardly. In its rearward position, the abutment 56 is removed from the path of the partially ejected pins 38, and the shaft 34 is rotated a complete revolution before the abutment 56 is moved to its normal position by the tension of the spring 57, subsequently to the ejection of the pins 38. The cam 51 is intermittently rotated on the shaft 34 with the wheel 36, moving the arm 48 of the register upwardly and permitting it to be moved downwardly under the influence of the spring 49, thus adding the total value of the coins ejected during the operation of the machine.

Having thus described the invention what I claim, is:—

1. In combination, a support, an ejector on said support, a registering mechanism on said support, operating means for said registering mechanism including a pivoted member operable by a coin ejected by said ejector, and means for automatically raising said pivoted member from engagement with the coin.
2. In combination, a support, coin ejectors operably mounted on said support, a registering mechanism on said support, operating means for said registering mechanism including a plurality of pivoted members adapted to be engaged by coins ejected by

said ejectors, and adjustable means for automatically disengaging said pivoted members from said coins.

3. In combination, a support, coin ejectors operably mounted on said support, a registering mechanism on said support, operating means for said registering mechanism including a plurality of pivoted members adapted to be engaged by coins ejected by said ejectors, and adjustable means for automatically disengaging said pivoted members from said coins including inclined surfaces on said support, and screws fitted in said pivoted members slidably upon said inclined surfaces.

4. In combination, a support, a plurality of coin ejectors operably mounted on said support, a registering mechanism on said support, operating means for said registering mechanism including a rotatable shaft, a wheel on said shaft, and means for locking said wheel against rotation, means operable by the coins ejected by said ejectors to actuate said locking means, and means operable by said coin actuated means for releasing said wheel.

5. In combination, a support, a plurality of coin ejectors operably mounted on said support, driving means for said coin ejectors, a registering mechanism on said support, operable connections between said coin ejectors and said registering mechanism, operating means for said registering mechanism including a rotatable shaft, a wheel on said shaft, a plurality of pins slidably mounted in said wheel, an abutment secured adjacent said wheel adapted to be engaged by said pins to lock said wheel against rotation, and means operable by the coins ejected by said ejectors for moving said pins to normal position to release said wheels.

6. In a coin counting machine, a support, a plurality of coin ejectors operably mounted upon said support, a registering mechanism on said support, means for simultaneously operating said coin ejectors and said registering mechanism, a wheel connected with said registering mechanism, a stop member associated with said wheel, means controlled by the coins ejected by certain of the ejectors for locking said wheel and registering mechanism against operation, and means operable by coins ejected by other of the ejectors for moving said stop member out of operative position.

7. A coin counting machine including a support, a plurality of coin ejectors operably mounted upon said support, a registering mechanism on said support, means for simultaneously operating said coin ejectors and said registering mechanism, a wheel connected with said registering mechanism, a stop member associated with said wheel, means operable by certain of the ejectors adapted to engage said stop member to lock

4
said wheel against rotational movement at predetermined points, and means controlled by the last-mentioned ejectors for moving said locking means to inoperative position 5 and including a universal bar pivotally supported upon said supports.

8. In a coin counting machine, a support, a plurality of coin ejectors operably mounted upon said support, a registering mechanism on said support, means for simultaneously operating said coin ejectors and said registering mechanism, a wheel connected with said registering mechanism, means operable by coins ejected by said ejectors for 10 locking said wheel and registering mechanism against operation, and means controlled by said locking means for releasing said wheel and including a pivoted stop member associated with the wheel and a universal bar connected with said stop member 15 and operable by said locking means.

9. In a coin counting machine, a support, a plurality of coin ejectors operably mounted upon said support, a registering mechanism on said support, a wheel connected with said registering mechanism, a plurality of stop members slidably mounted in said wheel, means controlled by the coins ejected by said ejectors for actuating said 20 slid able stop members, a pivoted stop member adapted to coöperate with said slid able stop members to lock said wheel against rotation.

10. In a coin counting machine, a support, a plurality of coin ejectors operably mount-

ed upon said support, a registering mechanism on said support, a wheel connected with said registering mechanism, a plurality of stop members slidably mounted in said wheel, and means controlled by the coin ejected by certain of said coin ejectors for 35 actuating said slid able stop members, a pivoted stop member adapted to coöperate with the slid able stop members to lock said wheel against rotational movement, and means operable by coins ejected by another of said 40 coin ejectors for moving said pivoted stop member to inoperative position.

11. In a coin counting machine, a support, a plurality of coin ejectors operably mounted upon said support, a registering mechanism on said support, a wheel connected with said registering mechanism, a plurality of stop members slidably mounted in said wheel, means controlled by said coins ejected by certain of said coin ejectors for 45 actuating said slid able stop members, a pivoted stop member adapted to coöperate with said slid able stop members to lock said wheel against rotational movement, and adjustable means operable by coins ejected by another 50 of said coin ejectors for moving said pivoted stop members to inoperative position.

In testimony whereof I affix my signature in presence of two witnesses.

IRA D. FULLER.
